CLAIM

The ornamental design for an egg carton with bubble cell pockets, as shown and described.

DESCRIPTION

FIG. 1 is a front top perspective view of an egg carton with bubble cell pockets;

FIG. 2 is rear top perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a bottom perspective view thereof.

The broken lines illustrate portions of the egg carton with bubble cell pockets and form no part of the claimed design.
